UNITED STATES PATENT OFFICE.

HENRY WESTENDORF, OF HALBUR, IOWA.

SUPPORTING FIXTURE FOR CLOSURE MEMBERS.

Application filed June 5, 1922. Serial No. 565,972.

To all whom it may concern:

Be it known that I, HENRY WESTENDORF, a citizen of the United States, residing at Halbur, in the county of Carroll and State 5 of Iowa, have invented certain new and useful Improvements in Supporting Fixtures for Closure Members, of which the following is a specification.

This invention relates to an improved supporting arrangement for closure members, such as screens, storm windows and storm doors.

The primary object of this invention is the provision of a novel supporting hinge, 15 whereby screens or storm doors and windows may be pivoted or hinged to a casing, so that they may be regulated in facile manner for closing or ventilating purposes, and whereby the screen or door may be readily 20 detached.

A further object of this invention is the provision of a hinge supporting arrangement for closure members, such as screens and storm doors and windows, used only at 25 certain seasons of the year, and which it is desirable to remove during certain periods; said supporting arrangement being of such character as to permit instant attachment or detachment of the closure member, as desired.

A further object of the invention is the provision of an improved supporting arrangement for closure members, whereby the closure member may be effectively swung or 35 slid out of the opening in which the same is positioned and maintained in a determined position for ventilating purposes.

Other objects and advantages of this invention will be apparent during the course 40 of the following detailed description.

In the accompanying drawing, forming a part of this specification, and wherein similar reference characters designate corresponding parts throughout the several 45 views:

Figure 1 is a front elevation of a building structure, showing a closure member supported in partly open position with respect to a supporting casing by improved fixtures.

50 Figure 2 is a fragmentary perspective view of certain sections of a supporting member and its supporting casing, showing the manner in which the leaves of a hinged section embodied in this invention cooperate in the support of the closure member.

Figure 3 is a transverse cross sectional

view of the adjacent portions of a closure member and its supporting casing, showing the novel type of hinge structure supporting the closure member in closed position. 60

Figure 4 is a front elevation of the details as illustrated in Figure 3.

Figure 5 is a perspective view of a hook member used as a detail of the improved supporting arrangement for closure members. 65

In the drawing, wherein for the purpose of illustration is shown the preferred embodiment of this invention, the letter A designates a building construction embodying a 70 casing B, in which a closure member C is provided, supported by hinges D. A fastening device E is preferably provided in connection with the casing B and its closure member C to maintain the latter in a determined opened or closed relation. 75

The hinges D will find their most general use in connection with the supporting of screens and storm doors which are used for certain seasons each year, and whereby the 80 screens or doors may be readily attached, detached, or regulated. Consequently, it is preferred that the casing B be a window casing embodying the side pieces 10 and 11, and within the opening 13 of which casing 85 B, the stop strips 14 are attached, in any preferred manner.

The closure member C may, of course, be of any type, such as a door, screen, or the like, and which includes a supporting frame 90 15 embodying side sections 16 and 17, and top and bottom sections 18 and 19 respectively. The closure member C is, of course, positioned within the plane of the opening 13, defined by the window casing B, so that 95 when the closure member C is shut within the opening 17, the outer surfaces of the sections of the closure member frame 15 preferably lie flush with the outer surface of the casing frame sections 10 and 11. In this position, the frame sections 10 and 16 of the casing B and closure member C respectively are in adjacent relation, whereas the frame sections 11 and 17 of the window casing B and closure member C are adjacently positioned; the latter sections 11 and 17 being those sections which receive the hinge members D in a manner to be subsequently described. 105

Referring to the improved type of hinge 110 D, the same includes leaves 20 and 21, respectively adapted for attachment to the

frame sections 11 and 17 of the casing B and closure member C. The leaf or section 20 is preferably formed of sheet metal stamped or bent to provide an attaching flange 22, which is provided with a plurality of openings therein for receiving screw elements 23 or the like, whereby the flange 22 may be secured upon the outer surface of the window side piece 11. An elongated loop portion 24 is provided as a part of the leaf 20, preferably integral with the attaching portion 22, and which is substantially one half of the vertical dimension of the attaching portion 22, the portions 22 and 24 being so formed as to have their lower marginal edges lying flush with each other. The loop portion 24 provides an elongated slot 26, and is disposed with its major axis at an obtuse angle with respect to the face of the casing 28 and extending beyond the plane of the jamb 28 of the casing as clearly shown in Figure 3. The loop 24 is, in fact, provided by bending the material thereof until the free end thereof is adjacently disposed with respect to the attaching portion 22, and substantially as is illustrated in Figures 2 and 3 of the drawings. When the leaf 22 is attached to the casing frame portion 11, a shoulder 27 is provided, which extends outwardly from the jamb 28 of the casing section 11, and against which the side piece 17 of the closure member frame 15 is adapted to cooperate in a manner to be subsequently described. When the leaf is attached upon the window casing B, the loop 24 thereof extends outwardly with respect to the plane defined by the attaching portion 22, and is inclined toward the opening 13 defined by the casing B.

Referring to the leaf or section 21, the same is of material similar to the leaf 20, and is stamped or otherwise formed with an attaching flange or portion 30 provided with suitable openings therein for receiving screws 31 or like elements, whereby the leaf 21 may be attached to the outer surface of the closure member frame section 17. A wing flange 32 is provided as a portion of the leaf 21, extending in a plane at an acute angle with respect to the plane defined by the attaching flange 30, and having a slot 34 extending upwardly therein from the lower marginal edge 35 of the leaf 21, to provide a projection or leg 36, which is provided for sliding reception within the slot 26 of the leaf section 20.

As is illustrated in Figure 1, the closure member C is provided with a pair of hinges D. The leaves 20 and 21 having been assembled upon the window casing B and closure member C respectively, it is merely necessary for an operator to dispose the legs or projections 36 of the leaves 21 in the outer portion of the guide slots 26 of the leaves 20, and it is obvious that the closure member

C will be supported by the hinge leaves 20. The position of the hinge leaf 21 during such attaching operation of the closure member C is indicated in the dotted lines in Figure 3 of the drawings. From this view, it can be seen that the closure member C is entirely removed from the opening 13 of the window casing B during an attaching operation, and whereby an operator may grasp the side sections 15 and 17 of the closure member frame 15 with ease, since a clearance is provided between the closure member and the window casing during such attaching operation. Due to the inclination of the slot 26, it is but necessary for an operator to grasp the outside section 16 of the window frame 15, in order to slide the leaf 21 longitudinally in the slots 26, until the projections 36 are disposed within the inside ends of the slots 26, so that the closure member C may be swung in the ordinary manner into closed or opened position. It is to be noted that when the closure member C is placed within the opening 13 to close the same, the edge portions of the closure frame section 17 is disposed in its engagement against the shoulders 27 provided by the fixed hinged sections 20, so that it is first necessary to oscillate or swing the closure member C, before the same may be slid longitudinally in the guide slots 26. In this manner, the attaching edge of the closure member C is prevented from swinging outwardly when the frame B is in closed position.

Referring to the fastening arrangement E, the same preferably includes a hook 40, and an eye bolt 41. The hook member 40 is preferably of wire, bent to provide an attaching eye portion 39, at one end thereof, and a latch projection 42 upon the other end thereof, adapted for cooperation in the eye bolt 41. The material of the hook 40, adjacent the eye 39, is bent to provide an arcuate extension 44, offset to a side of the plane of the attaching eye 39, and likewise adapted for cooperation in the eye of the bolt 41. It is preferred that the hook member 40 be attached to the outside of the stop bead or strip 14, adjacent the casing section 10; and the eye bolt 41 be attached to the inside of the closure member C, upon the section 16 of the frame thereof.

In operation, when the closure member C is entirely disposed within the opening 13 of the window casing B, the hook member E will be in a position as is illustrated in Figure 1 of the drawings, and in which position, the projection end 44 will be disposed within the eye of the bolt 41 for locking of the closure member C in position for sealing the casing opening 13. On the other hand, when it is desired to maintain the window or closure member C open for ventilating purposes, the same is swung upon the leaf

sections 20 and, if desired, may be swung so that the projections 36 are disposed in the outer ends of the guide slots 26. In this position, the hook member 40 can be so placed that the latch end 42 thereof is disposed within the eye of the bolt 41 and whereby the closure member C may be held in a fixed open relation to the window casing B, as can be readily understood.

- 10 From the foregoing, it can be seen that a supporting arrangement for closure members has been provided, embodying a plurality of novelly designed fixtures, which are relatively simple in construction, may be 15 economically manufactured, and which will effectively maintain the closure member C in relation to the casing B, so that the same may be instantly attached or detached as desired.
- 20 Various changes in the shape, size and arrangement of parts, may be made to the form of invention herein shown and described, without departing from the spirit of this invention or the scope of the claims.

25 I claim:

1. In a structure of the class described, the combination with a supporting casing defining an opening, and a closure member adapted for fitting into the opening; of a 30 hinge means connecting the closure member with the casing and including a hinge member secured to the casing and having an elongated loop portion with the major axis of its slot at an obtuse angle to the face of 35 the casing and extending beyond the plane of the jamb of the closure receiving opening, and a hinge member secured to the closure member and having a wing flange portion extending outwardly from the 40 closure member in spaced relation inwardly from the plane of the side edge thereof, said flange extending in crossed relation above the loop of the casing carried hinge member and provided with a depending leg 45 fitting into the slot thereof and mounting the closure member for swinging and sliding movement.

2. As an article of manufacture, a hinge leaf formed of sheet material providing a 50 flat attaching flange, and a tongue extending from the attaching flange and bent to ex-

tend from the attaching flange at an obtuse angle, said tongue being bent back upon itself with its free end in close proximity to the attaching flange and providing an elongated eye, the lower edge of said tongue being flush with the lower edge of the attaching flange and the upper edge of the tongue being in a plane below the plane of the upper edge of the attaching flange.

3. As an article of manufacture, a hinge construction comprising a leaf provided with an attaching flange, and an arm portion extending diagonally from one end of said attaching flange and having a slot extending at an obtuse angle with respect to the plane of the attaching portion, the arm portion having its lower edge flush with the lower edge of the attaching flange and its upper edge in spaced relation to the plane of the upper edge of the attaching flange, said hinge construction including a second leaf providing an attaching flange and having an outturned wing extending in converging and crossed relation to the slotted portion 75 of the first section and provided at its outer end with a depending leg adapted for pivotal and sliding movement within the slot of said first mentioned section.

4. In a device of the class described, the 80 combination with a casing and a closure member operating within an opening thereof, said casing and closure member when in assembled closed relation having the outer surfaces thereof in flush relation, of a hinge 85 construction embodying a leaf attached to said window casing and providing an outwardly extending slotted portion which overlaps and provides a shoulder against which a portion of the closure member rests 90 when in closed position, and a second leaf embodying an outwardly extending projection adapted for pivotal and sliding movement within the slot of the first mentioned section, said closure member when in the 95 casing in closed position resting against the shoulder of the first mentioned section, and adapted to be opened by first oscillating the same and then sliding the same bodily along the slotted portion of said first mentioned 100 section.

HENRY WESTENDORF.
